J. C. BENDER

CIGAR AND TOBACCO FLAVORING AND MOISTENING SUBSTANCE

Filed May 28, 1926

INVENTOR:
Joseph C. Bender
BY
Everett Rook, ATTORNEYS.

UNITED STATES PATENT OFFICE.

JOSEPH C. BENDER, OF UNION CITY, NEW JERSEY, ASSIGNOR, BY MESNE ASSIGNMENTS, TO THE RUMIDOR CORPORATION, A CORPORATION OF NEW JERSEY.

CIGAR AND TOBACCO FLAVORING AND MOISTENING SUBSTANCE.

Application filed May 28, 1926. Serial No. 112,229.

It has been common heretofore in the tobacco art to spray tobacco in the course of manufacture into various products with rum, a solution of rum or the like to give it a flavor, and furthermore various devices have been employed for introducing into cigar boxes and other containers for tobacco and tobacco products various forms of humidifiers for keeping the tobacco and products moist.

The objects of the present invention are to secure an improved substance which can be placed in a container for cigars or other tobacco products and not only serve to moisten them but also serve to impart to them the flavor of rum; to provide such a substance in the form of a solid containing rum and from which rum will evaporate under atmospheric conditions; to secure such a composition composed largely of liquid rum to which has been added a small proportion of solidifying agent, under heat, so as to form a substance which will become solid at room temperature; to thus provide a substance which when placed in a tobacco humidor or the like will both moisten the tobacco and flavor it with rum, and to obtain other advantages and results as may be brought out by the following description.

Referring to the accompanying drawings, in which like characters of reference indicate the same parts throughout the several views,

Figure 1 is a side view of a device containing my improved substance before it has been used;

Figure 2 is an end view of the same;

Figure 3 is a central longitudinal section of the same;

Figure 4 is a central longitudinal section of the device with its ends opened for use and the contents shriveled to a residue by evaporation through use of the device, and

Figure 5 is an end view of the same.

In said drawings, I have illustrated my improved substance and the use thereof by showing it contained in an open-ended tube 1, preferably of glass, which is filled with the substance 2 by introducing the same into the tube preferably in a fluid or flowing

condition and allowing it to harden therein. Then closures 3, 3 are applied one to each end of the tube, said closures being shown with a perforated crown 4 and an annular flange 5 to slidably fit the tube 1. These 55 closures 3, 3 may be of metal or any other suitable material, and for sealing them and their perforations to prevent any escape of moisture or flavor, such as would be caused by evaporation of the contents 2, said clos- 60 60 ures 3, 3 are each covered by a capes viscose cap 6, as it is known on the market, said cap 6 being formed of a substance such as cellulose hydrate which, when the cap is placed loosely over the end of the tube 1 and 65 its closure 3, contracts upon exposure to the atmosphere until it very tightly and im- perviously covers the same, as shown in Figure 3 of the drawings. Any other suitable seal could be used, however, and any suit- 70 able case other than a tube could be em- ployed.

The device as thus described is sold on the market and when the purchaser is ready to place it in a cigar box, for example, he 75 breaks the capes viscose cap 6 away from the perforated end 4 of the closure so as to open said perforations, as shown in Figures 4 and 5. Thereupon the substance 2 evaporates and its flavor and moisture is 80 imparted to the cigars. The contents of one of my improved devices will last for a long time, the substance 2 finally assuming a small shriveled form, something as shown at 85 7 in Figure 4, when it has lost its flavor and moisture and a new container full of my improved substance must be inserted in place of the exhausted one.

Obviously, more or less of the perforations in the end 4 of the closure can be 90 opened by breaking away the cap 6, as de- sired, so as to permit a faster or slower evaporation of the substance 2 and thus vary the strength of the flavor.

The substance 2 which is the particular 95 subject matter of the present application, the container which has been described in connection with its use being claimed in a separate application, is made from rum and the rum which I employ is necessarily 100

denatured rum by the present United States law, but otherwise it need not be denatured. It is treated in any suitable manner so as to cause it to become solidified or at least 5 jelly-like or of the consistency of soap, so that it is not a liquid and liable to be spilled. A suitable method of solidifying the rum is by heating it, adding approximately five per cent (5%) by weight of a 10 solidifying agent such as a neutral solution of sodium stearate, agitating and cooling. Another way to solidify the rum would be to add stearic acid and then a solution of caustic soda until neutral or not appreciably 15 either acid or alkali. In any event, the resulting substance is a solid at room temperature, and is about ninety-five per cent (95%) rum, so that under atmospheric conditions rum will evaporate from it about 20 the same as liquid rum would evaporate. This provides sufficient moisture for tobacco or cigars and at the same time gives them a flavor of rum.

Obviously various other distilled or 25 vinous liquors having suitable flavor and aroma can be employed instead of rum, without departing from the spirit and scope of the invention. Therefore, I do not desire

to be understood as limiting myself except as required by the following claims when 30 construed in the light of the prior art.

Having thus described the invention, what I claim is:

1. A substance for placing in tobacco humidors and the like to moisten the tobacco and flavor it with rum, consisting of a solid composition containing rum and from which rum will evaporate under atmospheric 35 conditions.

2. A substance for placing in tobacco 40 humidors and the like to moisten the tobacco and flavor it with rum, consisting of rum converted to a solid condition by the addition of a solidifying agent and the application of heat and in which condition 45 the rum will evaporate into the atmosphere of a room.

3. A substance for placing in tobacco humidors and the like to moisten the tobacco and flavor it with rum, consisting of a mixture of substantially 95% rum and the rest a solution of sodium stearate which mixture at room temperature and atmospheric conditions is a solid from which rum 50 will evaporate.

JOSEPH C. BENDER.
